(57) **CLAIM**

The ornamental design for a food and beverage tray with hinged lid, as shown and described.

DESCRIPTION

FIG. 1 is a right side elevational view of a food and beverage tray with hinged lid with the lid closed showing our new design, the left side elevational view being a mirror image thereof;

FIG. 2 is a top plan view thereof;

FIG. 3 is a front elevational view thereof;

FIG. 4 is a rear elevational view thereof;

FIG. 5 is a bottom plan view thereof;

FIG. 6 is a top plan view of the food and beverage tray with hinged lid opened showing our new design;

FIG. 7 is a cross-section view in elevation taken along line 7—7 of FIG. 6 thereof; and,

FIG. 8 is a front elevational view thereof.
